Primary Examiner—Philip S. Hyder

(74) Attorney, Agent, or Firm—Natalie D. Kadievitch;
Fredrickson & Byron, P.A.**CLAIM**

I claim the ornamental design for the organizer box, as shown and described.

DESCRIPTION

FIG. 1 is a perspective view of the organizer box of my design shown in an open state;

FIG. 2 is a perspective view of the organizer box shown in FIG. 1 with trays pivoted to an open positon;

FIG. 3 is a front view of the organizer box in a closed state;

FIG. 4 is a top view of the organizer box in a closed state;

FIG. 5 is a left side view of the organizer box in a closed state;

FIG. 6 is a back view of the organizer box in a closed state; and,

FIG. 7 is a bottomview of the organizer box in a closed state. The broken line portions of the disclosure are for illustrative purposes only and form no part of the claimed design.
